(57) **CLAIM**

The ornamental design for a wand for razor handle extension, as shown and described.

DESCRIPTION

FIG. 1 is a front elevational view of a wand for razor handle extension showing our new design; it being understood that the broken lines showing a razor are for illustrative purposes only and form no part of our invention.

FIG. 2 is a right side elevational view thereof, the left side being a mirror image thereof;

FIG. 3 is a rear elevational view thereof;

FIG. 4 is a bottom plan view thereof; and,

FIG. 5 is a top plan view thereof.
